UNITED STATES PATENT OFFICE.

HYMAN ELI GOLDBERG, OF CHICAGO, ILLINOIS, ASSIGNOR TO GOLDBERG CALCULATING MACHINE COMPANY, OF CHICAGO, ILLINOIS.

CALCULATING-MACHINE.

1,099,497.

Specification of Letters Patent.

Patented June 9, 1914.

Application filed September 1, 1911. Serial No. 647,214.

To all whom it may concern:

Be it known that I, HYMAN ELI GOLDBERG, a citizen of the United States, residing at Chicago, in the county of Cook and State 5 of Illinois, have invented certain new and useful Improvements in Calculating-Machines, of which the following is a specification.

In Patent No. 893,719, issued to John C. Wahl July 21, 1908, there is shown a type-writing, adding and subtracting machine. It consists of an ordinary Remington typewriter, to whose framework the master mechanism, including the master wheel, is 10 attached. To the carriage of the typewriter the totalizer of the calculating machine is attached. When the operator depresses the figure keys of the typewriter he rotates the master wheel, the teeth whereof engage the 15 carrying wheels mounted in the totalizer. As the carriage of the typewriter advances a step, the totalizer moves in unison therewith and the above-mentioned carrying wheel is disengaged from the master wheel 20 and the next carrying wheel brought into engagement therewith. And so on, successively. The totalizer has there been shown with its carrying wheels provided with thirty teeth. This is the form in which the 25 machine has been put upon the market. In Patent No. 893,720, issued to me July 21, 1908, is shown a similar machine with the totalizer calculating numbers not only to the base 10, but also those to the duodecimal 30 base, or 12. The duodecimal carrying wheel is shown with twenty-four teeth, while the decimal carrying wheels have only twenty teeth. There is thus introduced a variation in the gearing, which variation in practice is 35 annoying.

One of the objects of my invention is the construction of a totalizer capable of calculating duodecimally and having the gearing of its duodecimal carrying wheels of the 40 same size pitch and number of teeth as the gearing of its decimal carrying wheels.

More especially, one of the objects of my invention is the construction of a totalizer which has thirty teeth in its decimal carrying wheels, and the same number, thirty teeth, in its duodecimal carrying wheels.

Calculations to base-12 occur very commonly, for instance: in British currency, inches, gross, dozens, etc. But there are also 45 other bases larger than ten which are in use

to some extent. Thus base-16 is used in Hindoo currency, ounces, subdivisions of the yard, etc. Base-28 occurs in English avoirdupois weight, where the long ton of 2240 lbs. is divided into twenty cwt. and each 50 cwt. is divided into four quarters each of which equals 28 lbs. The standard arithmetical base is of course base-10. There are ten numerals corresponding to it, namely 0, 1, 2, 3, 4, 5, 6, 7, 8, and 9. The numeral 55 wheels of the totalizer are therefore ordinarily constructed large enough for this cycle of ten numerals. When the totalizer is constructed to calculate to the base-12, the numeral wheel must show the twelve numerals 0, 1, 2, 3, 4, 5, 6, 7, 8, 9, 10, and 11. This 60 might be done in the same sized numeral wheel with some crowding. But there is a limit to durable crowding. For instance: in a totalizer calculating to the base-28 the 65 numeral wheel must show the twenty-eight numerals 0, 1, 2, 3, 4, 5, 6, 7, 8, 9, 10, 11, 12, 13, 14, 15, 16, 17, 18, 19, 20, 21, 22, 23, 24, 25, 26, and 27. This cycle of numerals requires 70 much more room than the decimal cycle. I 75 have therefore invented means whereby I gain more room. This I accomplish by arranging the numerals not in one ring, as is usual, but in more than one ring. Thus in base-16 numeral wheels I arrange the numerals 80 in two rings namely 0, 1, 2, 3, 4, 5, 6, and 7 in one ring, and 8, 9, 10, 11, 12, 13, 14, and 15, in another ring, and provide indicating means for showing upon which of 85 these two rings the numeral of the total is 90 located. Similarly in a numeral wheel for base-28 I arrange the numerals in two rings 0, 1, 2, 3, 4, 5, 6, 7, 8, 9, 10, 11, 12, and 13 in one ring and 14, 15, 16, 17, 18, 19, 20, 21, 22, 23, 24, 25, 26 and 27 in another ring. 95 And this arrangement of the numerals in more than one ring is another object of my invention.

Bases larger than ten I call superdecimal bases. They differ from the decimal base 100 in the fact that more than one digit is required in order to express their highest number. Thus the highest number under base-10 is 9 which requires only one digit. The highest number under base-12 is 11, under base-16 is 15, under base-28 is 27. Each of the numbers 11, 15 and 27 requires two digits to express it, one digit for the units of the number and another digit for the tens thereof. In Patent 983,719, above 110

cited, there is shown a locking plate to the right of the master wheel, which plate serves to lock and aline all the non-working carrying wheels of the totalizer, namely those to the right of the master wheel. This construction is of great convenience. But in my Patent 893,720, above cited, the totalizer wheel of the duodecimal portion is made wider than the wheels of the decimal portions, in order to be operable by the master wheel in two distinct positions of the totalizer, one position to receive the tens of the duodecimal number, and the other position to receive the units of said number, as above indicated. This widening caused the abandonment of the above mentioned locking plate. This in practice was found to be quite annoying. I have therefore modified the above construction of the totalizer by the introduction of mechanism which permits the retention of the said locking plate even in totalizers calculating to superdecimal bases, and this improvement is another object of my invention.

25 The invention is illustrated by the accompanying drawings, of which,—

Figure 1 represents a front elevation of a Remington typewriter with a calculating attachment mounted thereon; Fig. 2 represents a side elevation of the totalizer of the calculating machine taken along the line 2—2 shown in Fig. 1, and also along the line 2—2 of Figs. 3, 4, 5, 6, and 7. Figs. 3, 4, 5, 6 and 7 show a development of the wheels of the totalizer in their proper relative lateral positions, but with the hubs and some of the gears widened out to leave more room between the parts and thus to better illustrate their coöperation; Fig. 3 represents the numeral wheels, Fig. 4 the intermediate wheels, Fig. 5 the carrying wheels, Fig. 6 the upper carrying pinions and their supporting arms, and Fig. 7 the lower carrying pinions and their supporting arms; and Figs. 8 to 18, inclusive, show views of some of the parts in order to more clearly illustrate their construction, as will be more fully explained below.

50 Mounted upon the framework 1 of the typewriter is the master mechanism 2 of the calculating machine. This master mechanism includes the master wheel 3, and the locking plate 4 which is located immediately to the right thereof. The master mechanism is connected to the figure keys 5 of the typewriter by the links 6. Whenever a figure key 5 is depressed, the mechanism is set in operation, and as a result the master wheel 3 is rotated an amount corresponding to the value of the figure key depressed. The typewriter is provided with keys which print 0, 1, 2, 3, 4, 5, 6, 7, 8, 9, and 1, and whose values are 0, 1, 2, 3, 4, 5, 6, 7, 8, 9 and 10. Attention is directed to the fact that there is among the figure keys a key which

prints 1 but whose value is 10. This is thoroughly shown in my Patent No. 893,720. This key is used in the printing and calculating of the tens portion of bases larger than 10, or superdecimal bases, among which 70 I include the base-12, the base-16 and the base-28. Connected to the carriage 7 of the typewriter is a bar 8 which travels therewith. Mounted upon the bar 8 is the totalizer 9, which thus also travels with the typewriter carriage during the letter-space advance thereof. The totalizer contains carrying gears which pass by and mesh with the master wheel during the operation of the machine. This has been thoroughly 80 shown in the above cited patents, and will therefore not be further described.

Mounted in the totalizer upon suitable shafts are the numeral wheels 10 (Fig. 2), the intermediate wheels 11, the carrying wheels 12, the upper swing arms 13 and the lower swing arms 14. The numeral wheels 10 are of three different kinds (Fig. 3). There are some of the ordinary decimal kind 101 (Fig. 16) each of which is composed of 90 a numbered cylinder 102 with the ten numerals 0, 1, 2, 3, 4, 5, 6, 7, 8 and 9 thereon, and a ten toothed gear 103 rigidly fastened thereto. There is the duodecimal numeral wheel 104 (Fig. 18) with the twelve numerals 0, 1, 2, 3, 4, 5, 6, 7, 8, 9, 10 and 11, which has rigidly fastened thereto the twelve-toothed gear 105. There is the numeral wheel 106 (Fig. 17) calculating to the base-16, which has thereon two numeral cylinders, namely, the cylinder 107 with the numerals 0, 1, 2, 3, 4, 5, 6 and 7 thereon, and the cylinder 108 with the numerals 8, 9, 10, 11, 12, 13, 14 and 15 thereon, and which has rigidly attached thereto the eight-toothed gear 109. Meshing with the gears of the numeral wheels are the set of intermediate gears 11. These gears are provided with teeth, and the number of these teeth may be anything suitable. The gears 111 meshing with the decimal figure wheels are here provided with fourteen teeth (Figs. 4 and 14). The gear 112 (Figs. 4 and 15) meshing with the gear wheel 109 of the numeral-wheel calculating to the base-16 is made of a slightly different shape in order to mesh properly with the eight-toothed gear upon said numeral-wheel. The gear 113 (Fig. 4) meshing with the gear 105 upon the duodecimal wheel is made in two portions rigidly fastened together, 114 and 115, but this is simply for convenience in order to more readily gear with and clear the portions of the carrying wheels.

115 The carrying wheels 12 are of different kinds. There are the decimal carrying wheels 120, (Figs. 5 and 11), each one of which is composed of a thirty-toothed portion 121, a three-toothed portion 122, and a three scalloped portion 123. The thirty- 120

toothed portion 121 is to mesh with the intermediate gear 111 aforementioned. The base-16 carrying wheel (Figs. 5 and 12) is composed of a thirty-two-toothed portion 124, a two-toothed portion 125, a two-scalloped portion 126, and a cam 127, rigidly fastened together. To the right of the last-mentioned base-16 carrying wheel is an auxiliary idle gear 128 which may have any number of teeth, but in this particular case is provided with thirty teeth, for uniformity with the number of teeth with which the decimal carrying wheels are provided in this case. To the right of the idle gear 128 is a carrying wheel 130 (Fig. 13), which is composed of a thirty-toothed gear 131, a fifteen-toothed gear 132, and a fifteen-scalloped piece 133, the three pieces being rigidly fastened together. To the right of the last-mentioned wheel is the carrying wheel 134. It is composed of a thirty-toothed gear 135, a five-toothed carrying wheel 136, and a five-scalloped piece 137, all rigidly fastened together (Fig. 10). To the right of the last-mentioned gear is the auxiliary idle gear 138, which again may have any number of teeth, but is here provided with thirty teeth, for the reason given in connection with wheel 128.

30 The intermediate wheels 111 and 112 mesh with the gears of the numeral wheels on one side and with the gears of the carrying wheels on the other side. As before mentioned, the intermediate wheel 113 has two gear wheels 114 on one side which meshes with the gear 105 of the numeral wheel 104, and the gear 115 on the other side meshing with the gear 135 of the carrying wheel 134. The rotation of the decimal numeral wheel 101 is therefore always in unison with that of the decimal carrying wheel 120, the rotation of the base-16 numeral wheel 106 with that of the base-16 carrying wheel 124, and the rotation of the base-12 numeral wheel 104 in unison with the carrying wheel 134. The carrying wheel 130 is not directly geared with any numeral wheel and it serves to help in "carrying" but not in "indicating" the numerals. As the decimal wheels 120 have three carrying teeth for thirty teeth in the complete circumference, they will carry once for every ten steps, and will thus operate decimal. The base-16 carrying wheel 124 being provided with two carrying teeth in a complete circumference of thirty-two teeth, will carry at every sixteen steps, and will thus calculate for the base-16. The operation of the duodecimal portion, being more complicated, will be taken up in greater detail.

It happens that the number 12 can be factored. Thus 12 equals 2 times 6, or, again, 12 equals 3 times 4. It has been mentioned before that in the machine on the market, 65 which is the one illustrated in Patent No.

893,719, above cited, the decimal carrying wheels were provided with thirty teeth, and it will be noticed that one pair of the factors of 12, namely 2 and 6 are also factors of the number 30, and advantage has been taken of this fact in order to construct the duodecimal carrying portion of the mechanism with carrying wheels of thirty teeth each. This has been done by the use of two carrying wheels, instead of one carrying wheel, 75 as is usual. One of the carrying wheels carries at every second step, and the other carrying wheel carries at every sixth step, and the two together thus carry at every 2 times 6, or twelfth step. The wheel 130 is 80 the one that carries at every second step, for it has thirty teeth in its circumference, and is provided with fifteen carrying teeth. The wheel 134 is the one that carries at every sixth step, for it has thirty teeth in its circumference, and is provided with five carrying teeth. It will thus be seen that the pair of wheels 130 and 134 taken together operate to carry at every twelfth step or duodecimally. By the construction just described, I thus am able to "carry the twelves" by the employment of carrying wheels of the same sized gears as the decimal carrying wheels. This was stated above to be one of the objects of my invention. 95 Again more especially, I am enabled to carry twelves by the employment of thirty-toothed carrying wheels which also was stated above to be another object of my invention.

The function of the auxiliary idle wheels 100 128 and 138 will now be explained. It will be seen that each of these idle wheels is located immediately to the right of a carrying wheel which helps to carry to a superdecimal base, (that is, a base larger than 10). 105 Thus the wheel 128 is located immediately to the right of the superdecimal base-16 carrying wheel 124, and the wheel 138 is located immediately to the right of the superdecimal base-12 pair of carrying wheels 110 130 and 134. All superdecimal bases, being larger than 10, have two figures in their largest numerals. Thus 15 has two figures and 11 has two figures. In the operation of the machine here described, the tens figure of the superdecimal base is transmitted into the totalizer by the direct rotation of the superdecimal carrying wheel, which at that moment is directly in mesh with the master wheel. The units figure of the superdecimal number, however, is not transmitted directly but indirectly, namely, by the intermediation of the auxiliary gear, which auxiliary gear is at that moment directly in engagement with the master wheel. 115 120

As thoroughly described in the above cited Patent No. 893,719, and many others, the actual carrying from one carrying wheel to the next higher carrying wheel is done 130 through the intermediation of a set of car-

ried pinions 20. Figs. 8 and 9 show these pinions from the left and right sides, respectively. These are shown as arranged in two groups, but this is simply for the sake of gaining room. Each carried pinion is adapted to be rotated upon its support, independently of the others, and each serves to transmit the "carrying" from its co-operating lower carrying wheel at the right to its cooperating higher carrying wheel at the left. In function, these carried pinions act as idle wheels in that they serve to transmit and not to originate motion.

It will be noticed that some of the carrying pinions are wider than others, but this is simply a matter of convenience on account of the spacing of the numeral wheels and carrying wheels. It will, moreover, be noticed that the auxiliary gears 128 and 138 are wider than the gears upon the carrying wheels. In fact the auxiliary gears might each be considered as a wheel composed of a thirty-toothed gear at the right, a thirty-toothed gear in the middle, and a thirty-toothed scalloped piece at the left. The thirty scallops of this imaginary piece at the left run into each other and this piece therefore becomes reduced to the hub of the wheel. The thirty-toothed gear at the middle and the thirty-toothed gear at the right coalesce into a wide thirty-toothed gear as shown in the drawing (Fig. 5). The two gears 128 and 138 might therefore be considered as two carrying wheels, each carrying at every step thereof. Being such carrying wheels, they naturally co-operate with their own co-operating carried pinions 21 and 22, in precisely the same manner as the other carrying wheels. This co-operation has already been thoroughly explained in the above cited patents and therefore will not be further explained.

In practice, in the putting down of a number, 27 4 11 for instance, 27 rupees, 4 annas and 11 pie, the operator first would strike the 2 key, and the master wheel would therefore rotate the wheel 120 two steps and the numeral wheel 101 would indicate 2. Similarly, for the 7. The operator would then strike the space bar of the typewriter. During this interval the master wheel would not be in engagement with any carrying wheel, but would be immediately to the left of the carrying wheel 124. The operator would then strike either the 0 key of the typewriter, in order to insert the 0 of the 04 annas in the machine, that is, print a 0, but not rotate the wheels of the totalizer, or would simply strike the space bar again. In either case the master wheel will not have been rotated. During this period, the master wheel would have been in engagement with the carrying wheel 124. The operator would then strike the 4 key, which would rotate the master wheel, which now being in mesh

with the auxiliary gear 128, would rotate it an equal amount. The rotation of the idle gear will be transferred through the carrying pinion 22 into the carrying wheel 124, which will thus rotate four steps, and the numeral wheel 106 would rotate an equal amount because of the intermediate wheel 112. Upon the operator's removing his fingers from the figure key of the typewriter, the carriage would advance one step, and the totalizer would locate itself with the carrying wheel 130 in mesh with the master wheel. The operator would then strike the space bar, allowing the carriage to advance one step and moving the carrying wheel 130 out of and the carrying wheel 134 into mesh with the master wheel. The operator would then strike the tens key on the typewriter, whereby the master wheel would rotate ten steps, while there would be printed upon the paper the figure 1. The rotation of the master wheel is taken up by the rotation of the carrying wheel 134, which thus also rotates ten steps. When the operator removes his finger from the key, the carriage would again advance another step, removing the carrying wheel 134 out of and bringing the auxiliary gear 138 into mesh with the master wheel. The operator would then strike the 1 key of the typewriter, which would rotate the auxiliary gear 138 one step, and it in turn, by the intermediation of the carrying pinion 21, would rotate the carrying wheel 134 one step. The carrying wheel 134 will thus have imparted to it a total rotation of eleven steps, ten steps because of the striking of the tens key, which rotation was imparted to it by the master wheel directly, and one more step because of the striking of the 1 key, which added rotation was imparted to it through the intermediation of the auxiliary gear 138 and the carrying pinion 21.

It has been pointed out above that the base-16 numeral wheel, which has thereon the numerals 0, 1, 2, 3, 4, 5, 6, 7, 8, 9, 10, 11, 12, 13, 14, and 15, has its set of numerals divided into two groups, 0, 1, 2, 3, 4, 5, 6, 7, on one group and 8, 9, 10, 11, 12, 13, 14, 15 on the other group. So far, there has been described no mechanism whereby the operator can tell upon which of these two groups the numeral of the total is located. Such mechanism has been provided, and its consists of the cam 127, previously mentioned as being rigidly fastened to the carrying wheel 124, and the pointer 150 co-operating therewith. A spring 151, (Fig. 1), keeps the pointer pressed against the cam. The cam 127 moves the pointer 150 upon its support to indicate either the one ring of numerals or the other, as clearly shown in Figs. 5 and 3. Because carrying wheel 124 has thirty-two teeth and because the base-16 numeral wheel has only eight teeth, the

cam 127 has been provided with two rises and two falls, each of these rises and falls occupying one quarter of the circumference. Therefore for one quarter of the circumference of the wheel 124, the pointer 150 points to one ring of numerals of the numeral wheel; for the next quarter, to the other ring; for the third quarter, to the first ring again; and for the last quarter, to the second ring again.

An example will now be given of the operation of the totalizer during the addition of two numbers.

Suppose it is desired to add 27 rupees, 4 annas, and 11 pie (the number used above as illustrative) and 34 rupees, 15 annas and 3 pie. The operation of the addition of the rupees, namely, 27 rupees and 34 rupees, is ordinary, and is thoroughly shown in many patents, among them the previously cited Patent No. 893,719. As above explained, during the operation of entering the first number upon the totalizer, the 4 (of the 4 annas) is placed upon the carrying wheel 124, that is, the carrying wheel 124 is rotated four steps from its zero position. The numeral wheel 106 is thus also rotated four steps from its zero position, and the pointer 150 points to the numeral 4 upon the first ring. During the striking of the second number, the 1 (of the 15 annas) is placed upon the carrying wheel 124 by the striking of the tens key. The wheel 124 therefore receives an added rotation of ten steps, or thus far a total rotation of fourteen steps. During the striking of the 5 of the 15 annas, the carrying wheel 124 receives an additional rotation of five steps, and its total rotation will therefore be 19 steps. But since it carries at every sixteen steps, it will have carried 1 into the rupee, and now will be located at three steps from its zero position, as is proper. The numeral wheel 106 will meanwhile also have rotated nineteen steps, but as its cycle also is sixteen, it also will indicate a 3. The pointer 150 will have risen and fallen over the cam 127 and will now again point to the lower figured ring. During the striking of the first number, the 11 pie will have been properly introduced into the totalizer by the striking of the tens key, and the consequent rotation of the wheel 134 ten steps, and the subsequent striking of the 1 key and the consequent rotation of the wheel 134 one additional step through the intermediation of the auxiliary gear 138. The carrying wheel 134 will thus have received, so far, a total rotation of eleven steps, and the numeral wheel 104 in gear therewith will thus indicate an 11. During the subsequent striking of the 3 of the second number, the carrying wheel 134 will have received an additional rotation of three more steps, or a total rotation of fourteen steps. Similarly,

the duodecimal numeral wheel 104 will thus have received an equal rotation of fourteen steps, but as its cycle is 12, it will indicate a 2, which is proper. The operation of the wheel 134 was as follows: During its original rotation of ten steps, due to the striking of the tens key of the 11 pie, it will have been rotated ten steps, and as it carries at every sixth step, it will have carried 1 into the carrying wheel 130, leaving 4 as a remainder upon itself. The next rotation of one step, due to the 1 of the 11 pie, will leave the wheel 130 unchanged, but will bring the wheel 134 to five steps from its zero position. The additional rotation of three steps, due to the striking of the 3 of the second number, will thus bring the wheel 134 eight steps from its zero position, but as its cycle is 6, it will carry another 1 into the wheel 130, and thus there will be 2 left as a remainder upon the wheel 134. The final result upon the wheel 134 is therefore that it will be two steps from its zero position, which is proper. The wheel 130 will thus have received two carryings from the wheel 134, but the cycle of the wheel 130 is 2, and it will therefore have carried 1 into the next higher wheel, which in this case is 128. The wheel 128 carries at every step, and therefore immediately rotates the wheel 124 one step. The final result upon wheel 130 is therefore that it is left in its zero position and that the wheel 124 will have received an additional step, by the carrying of the twelves or pie, which is proper. The final result upon the totalizer will therefore be 62 4 2, or 62 rupees, 4 annas and 2 pie. As thoroughly described in Patent No. 893,719, it is necessary to disconnect the carrying wheel which is being rotated by the master wheel from the carrying wheel, or wheels to the right. As there shown, this is accomplished by removing the co-operating carried pinion out of mesh from the co-operating carrying wheels, and this in turn is accomplished by the swinging of the supporting swing arm 13 or 14 upon its shaft, each carried pinion being mounted upon a stud upon its swing arm. The same mechanism, without any change, is operative, to break the connection between the carrying wheel 124 and its co-operating auxiliary gear 128 to remove the carried pinion 22, by the swinging of its supporting swing arm. This, of course, occurs when the master wheel is in engagement with the carrying wheel 124. Therefore, whenever carrying wheel 124 is directly in mesh with the master wheel and is rotated thereby, its co-operating auxiliary gear 128 is stationary. That is, wheel 128 is stationary as long as it is to the right of the master wheel. It therefore in this respect behaves just as though it were any ordinary carrying wheel, and therefore there is no interference between 130

it and the locking plate 4 (Fig. 1) mentioned above as being to the right of the master wheel. And similarly for the auxiliary gear 138. The locking plate 4 may be and is retained without any change, and this was stated above to be another object of my invention.

A few obvious modifications will now be pointed out.

10 In a base-28 numeral wheel there occur the numerals 0, 1, 2, 3, . . . 26 and 27. These might be arranged in two rings having the numerals 0, 1, 2, . . . 12 and 13 on one ring, and the numerals 14, 15, . . . 25, 15 26, and 27 on the other ring. Again they might be arranged in four rings of numerals, thus 0, 1, 2, 3, 4, 5, and 6 on the first ring, 7, 8, 9, 10, 11, 12, and 13 on a second, 14, 15, 16, 17, 18, 19, and 20 on a third, and 20 21, 22, 23, 24, 25, 26, and 27 on the fourth. Of course, the carrying wheel will have to be constructed to carry at every twenty-eighth step. The cam 127 will also have to be suitably modified. In case the numerals 25 will be arranged in two ring-groups, the cam 127 need be provided with but two dwells so that the pointer 150 will point to either the one ring or the other. In case the numerals will be arranged in four ring-groups, 30 the cam 127 will be provided with four dwells so that the pointer will point successively to the four different numeral rings.

As shown above, a pointer has been used to indicate on which of the numeral rings 35 the numeral of the total has been located. This indicating means need not be a pointer. It might equally well be a shutter which would shut out from view the undesired rings and expose only the proper numeral 40 ring. Again, the pointer has been shown to be operated by a spring 151. This construction can be easily modified. The cam 127 might be made double-acting so as to drive positively in both directions, and the pointer 45 spring thus be rendered superfluous. The indicator would then be positively held in all of its positions.

In the calculation of pounds, shillings, and pence, (whose table is—20 shillings, 50 one pound; 12 pence, one shilling), it is customary to represent the shillings on two distinct wheels of which the lower or units shillings wheel calculates to the base 10, while the higher or tens shillings wheel calculates to the base 2. (See my Patent No. 893,720, above cited.). Attention is here directed to the fact that there is a vital difference between the decomposition of the base 20 into 2×10 , and the base 12 into 60 2×6 . This is due to the fact that the digits composing the numerals are always understood to be decimal. For instance, eleven shillings and eleven pence both are represented ordinarily by 11, in spite of the fact 65 that in shillings, the base is twenty, and

that in pence the base is twelve. This difference can be felt much more forcibly upon comparing the representation of the numerals upon the numeral wheels. There is no difficulty whatever in representing the 70 shillings upon two numeral wheels the lower one of which has the numerals 0, 1, 2, 3, 4, 5, 6, 7, 8, and 9 for its cycle, and the higher one of which has the numerals 0, and 1 for its cycle. In the operation of the machine, 75 these two numeral wheels move relatively to each other. Any attempt to represent the numerals corresponding to the base-12, in a similar manner upon a plurality of numeral wheels, which numeral wheels 80 in operation move relatively to each other, fails. This is because 20 is decomposable into factors 2×10 , each of which is a factor of 10. It is true that 12 is decomposable into factors, namely, 2×6 , but 85 not all of these factors are factors of 10. 2 is a factor but 6 is not, and if 6 be decomposed again into 2 and 3, then again 3 is not a factor. In other words base 12 finally contains some factor, namely 3, prime to 10. 90 Similarly, for base 28 in which 7 is prime to 10. It might therefore be said that base 20 is completely reducible while bases 12, and 28 are not completely reducible. They might therefore be called irreducible bases. 95

I am well aware that I am not the first to have used a plurality of carrying wheels for calculation to reducible bases, but as far as I know, I am the first to use plurality of carrying wheels for calculation to irreducible bases, and I therefore claim the idea broadly.

I claim—

1. In a totalizer having a portion which is adapted to calculate numbers to an irreducible base, a carrying wheel for said portion, said wheel having a gear formed integrally therewith to be driven thereby, and the number of teeth of said gear is such that when said number and said base are divided by their greatest common divisor the quotients are prime to each other.

2. In a totalizer having a portion which is adapted to calculate numbers to a duodecimal base, a carrying wheel for said portion, said wheel having a gear formed integrally therewith to be driven thereby, the number of teeth of said gear being such that when said number and 12 are divided by their greatest common divisor the quotients are prime to each other.

3. In a totalizer having a portion which is adapted to calculate numbers to an irreducible base, a carrying wheel for said portion, said carrying wheel carrying in a cycle whose number is a divisor of, and less than said base.

4. In a totalizer having a portion which is adapted to calculate duodecimal numbers, a carrying wheel for said portion, said

- carrying wheel carrying in a cycle whose number is a divisor of, and less than 12.
5. In a totalizer having a portion which is adapted to calculate duodecimal numbers, a plurality of carrying wheels for said portion and carrying mechanism connecting said carrying wheels, one of said carrying wheels operating its associated carrying mechanism every sixth step.
10. 6. In a totalizer having a portion which is adapted to calculate duodecimal numbers, a plurality of carrying wheels for said portion, and carrying mechanism connecting said carrying wheels, one of said carrying wheels operating its associated carrying mechanism every second step.
15. 7. In a totalizer having a portion which is adapted to calculate duodecimal numbers, a plurality of carrying wheels for said portion, carrying mechanism connecting said carrying wheels, one of said carrying wheels being a 30 toothed driving gear having five carrying teeth.
20. 8. In a totalizer having a portion which is adapted to calculate duodecimal numbers, a plurality of carrying wheels for said portion, carrying mechanism connecting said carrying wheels, one of said carrying wheels having thirty driving teeth and fifteen carrying teeth.
25. 9. In a totalizer having a portion which is adapted to calculate numbers to an irreducible base, a plurality of carrying wheels for said portion, each of said wheels carrying in a cycle having a number of steps which is a divisor of, but less than the base.
30. 10. In a totalizer having a portion which is adapted to calculate numbers to an irreducible base, a plurality of carrying wheels for said portion, the plurality as a totality carrying in a cycle which is equal to the base.
35. 11. In a totalizer having a duodecimal portion, two carrying wheels for said portion, one wheel being operative on the other to carry it.
40. 12. In a totalizer having a duodecimal portion, two carrying wheels for said portion, one wheel carrying at every sixth, the other at every second step.
45. 13. In a totalizer having a duodecimal portion, two carrying wheels for said portion, both wheels as a totality carrying at every twelfth step.
50. 14. In a totalizer, a carrying wheel and a numeral wheel geared thereto; the number of rotation steps necessary for a complete cycle of the carrying wheel being a factor of and less than the number of rotation steps necessary for a complete revolution of the numeral wheel.
55. 15. In a totalizer, a carrying wheel and a numeral wheel geared thereto; the number of rotation steps necessary for a complete cycle of the carrying wheel being a factor of and less than the number of numerals upon the numeral wheel.
60. 16. In a totalizer a carrying wheel and a numeral wheel geared thereto, the numerals on said numeral wheel being in cycles of twelve, and the number of teeth on said gear being such that said number and twelve have at least one common factor and when both the number and twelve are divided by their greatest common divisor the quotients are prime to each other.
65. 17. In a totalizer a 30 toothed carrying wheel, a numeral wheel of 12 teeth geared thereto, a second carrying wheel of 30 teeth, and carrying mechanism between said carrying wheels such that twelve steps advance of said first carrying wheel advances said second carrying wheel through one cycle.
70. 18. In a calculating machine, a totalizer including a portion which calculates to a decimal base, and another portion which calculates to a duodecimal base, carrying wheels for the decimal portion, other carrying wheels for the duodecimal portion, and a master wheel to operate said carrying wheels, each of said carrying wheels being provided with a gear for engagement with the master wheel, and all of said gears being equal in shape and each provided with thirty teeth for the purpose described.
75. 19. In a calculating machine, a totalizer including a portion which calculates to the base 10, and another portion which calculates to the base 12, carrying wheels for each portion, a master gear to operate said carrying wheels, by means of equal gears with which said carrying wheels are provided and formed integrally with them, the number of teeth in each of said gears being thirty.
80. 20. In a totalizer, carrying wheels calculating to a base greater than ten, and a units auxiliary wheel for the carrying wheels; the auxiliary wheel driving the carrying wheels for the units numerals of the base, but not so driving them for the tens numerals thereof.
85. 21. In a calculating machine, a carrying wheel calculating to a base greater than ten, a units auxiliary wheel for said carrying wheel, and a master mechanism rotating said carrying wheel for the tens of the base without rotating said auxiliary wheel, but rotating both the auxiliary wheel and the carrying wheel for the units of said base.
90. 22. In a calculating machine, a carrying wheel calculating to a base greater than ten, a units auxiliary wheel for the carrying wheel, and a master wheel operative on each of the said wheels; the carrying and auxiliary wheels being disconnected during the operation of the master wheel on the carrying wheel, but connected during the operation of the master wheel on the auxiliary wheel.
95. 100. 105. 110. 115. 120. 125. 130.

23. In a calculating machine, a carrying wheel calculating to a base greater than ten, a units auxiliary wheel for said carrying wheel, a master gear driving the carrying wheel for the tens numerals of the base and driving the units auxiliary wheel for the units numerals of the base, and means for connecting the carrying and units auxiliary wheels when the latter is driven by master wheel, and for disconnecting them when the former is so driven.
24. In a calculating machine, a wheel calculating to a base greater than ten, a units gear for moving the wheel for the units numerals of the base, and a tens gear for moving the wheel for the tens numeral of the base, the units gear being disconnected from the wheel during its movement by the tens gear.
25. In a calculating machine, a wheel calculating to a base greater than ten, a units gear for moving the wheel for the units numeral of the base, and a tens gear for moving the wheel for the tens numeral of the base; the units gear being stationary during the tens motion of the wheel.
26. In a calculating machine, a wheel calculating to a base greater than ten, a units gear for moving the wheel for the units numerals of the base, a tens gear for moving the wheel for the tens numeral of the base, and means for disconnecting the units gear from the wheel during its motion by the tens gear.
27. In a calculating machine, a numeral wheel calculating to a base larger than ten, a tens gear operative on the numeral wheel and serving to rotate it for the tens numerals of the base, a units gear adapted to operate on the numeral wheel and to rotate it for the units numerals of the base, a master gear adapted to engage each of said gears, a means for disconnecting and locking the units gear during the rotation of the tens gear by the master gear.
28. In a calculating machine: a carrying wheel calculating to a base greater than ten; a tens gear for driving the carrying wheel for the tens of the base; a units auxiliary gear for driving the carrying wheel for the units of the base; a master wheel for driving the tens gear and the units gear; means for connecting the carrying wheel and the units gear when the latter is in engagement with the master wheel; and means for disconnecting the carrying wheel and the units gear, and for locking said units gear when the master wheel is in engagement with the tens gear.
29. In a calculating machine: a carrying wheel calculating to a base greater than ten; a tens gear for driving the carrying wheel for the tens of the base; a units auxiliary gear for driving said carrying wheel for the units of said base; a master wheel for driving the tens gear and the units gear; means for connecting the carrying wheel and the units gear when the latter is in engagement with the master wheel; and means for disconnecting the carrying wheel and the units gear when the master wheel is in engagement with the tens gear; and a locking plate for locking said units gear during said period.
30. In a calculating machine, a numeral wheel adapted to be given a definite number of rotation steps to perform a complete revolution, and bearing a series of different numerals corresponding to a given base, the number of rotation steps being a divisor of the base, and means for operating the numeral wheel.
31. In a calculating machine, a numeral wheel bearing the series of different numerals corresponding to a given base, said series of different numerals occupying more than one complete circumference upon the numeral wheel, and means for operating the numeral wheel.
32. In a calculating machine, a numeral wheel bearing the series of numerals corresponding to a given base, said series of numerals being aliquotly subdivided into two or more groups, the numerals of each group occupying a complete circumference upon the numeral wheel, means for operating the numeral wheel, and an indicator to indicate the group in which the numeral is contained.
33. In a calculating machine, a numeral wheel bearing the series of numerals corresponding to a given base, said series being aliquotly subdivided into groups, the numerals of each group being located on the numeral wheel in a different ring portion, means for operating the numeral wheel, and an indicator determining in which ring portion the numeral is contained.
34. In a calculating machine, a numeral wheel bearing the series of different numerals corresponding to a given base, said series of numerals being aliquotly subdivided into two or more groups, the numerals of each group occupying a complete circumference upon the numeral wheel, and means for operating the numeral wheel.
35. In a calculating machine, a numeral wheel bearing the series of different numerals corresponding to a given base, said series being aliquotly subdivided into groups, the numerals of each group being located on the numeral wheel in a different ring, and means for operating the numeral wheel.
36. In a calculating machine a numeral wheel calculating to the base 28 and bearing a series of 28 numbers thereon, said series being divided into two equal groups, a shift-

- able indicator arranged to designate one of said groups and means to operate said numeral wheel and indicator.
37. In a calculating machine a numeral wheel calculating to the base 28 and bearing a series of 28 numbers thereon, said series being divided into two equal groups, each of said groups being laterally off-set upon said numeral wheel, a shiftable indicator arranged to designate one of said groups, and means to operate said numeral wheel and indicator. 55
38. In a calculating machine: a numeral wheel bearing the series of numerals corresponding to a given base, said series of numerals being aliquotly subdivided into two or more groups, the numerals of each group occupying a complete circumference upon the numeral wheel; means for operating the numeral wheel; an indicator to indicate the group in which the numeral is contained; and mechanism connected to said numeral wheel for operating said indicator. 60
39. In a calculating machine: a numeral wheel bearing the series of numerals corresponding to a given base, said series of numerals being aliquotly subdivided into two or more groups, the numerals of each group occupying a complete circumference upon the numeral wheel; means for operating the numeral wheel; an indicator to indicate the group in which the numeral is contained; and a cam connected to said numeral wheel for operating said indicator. 65
40. In a calculating machine: a numeral wheel bearing the series of numerals corresponding to a given base, said series being aliquotly subdivided into groups, the numerals of each group being located on the numeral wheel in a different ring portion; means for operating the numeral wheel; an indicator determining in which ring portion the numeral is contained; and mechanism connected to said numeral wheel for operating said indicator. 70
41. In a calculating machine; a numeral wheel bearing a series of numerals corresponding to a given base, said series being aliquotly subdivided into groups, the numerals of each group being located on a 75
- numeral wheel in a different ring portion means for operating the numeral wheel; an indicator determining in which ring portion the numeral is contained; and a cam connected to said numeral wheel for operating said indicator.
42. In a calculating machine a numeral wheel calculating to the base 28 and bearing a series of 28 numbers thereon, said series being divided into two equal groups, 80 a shiftable indicator arranged to designate one of said groups, a cam connected to said numeral wheel and arranged to operate said indicator, and means to operate said numeral wheel. 85
43. In a calculating machine a numeral wheel calculating to the base 28 and bearing a series of 28 numbers thereon, said series being divided into two equal groups, each of said groups being laterally off-set upon 90 said numeral wheel, a shiftable indicator arranged to designate one of said groups, a cam connected to said numeral wheel and arranged to operate said indicator, and means to operate said numeral wheel. 95
44. In a totalizer having a portion which is adapted to calculate duodecimal numbers; a plurality of carrying wheels for said portion, said plurality including two carrying wheels one of said carrying wheels having a thirty toothed driving gear and five carrying teeth, the other of said carrying wheels having a thirty toothed driving gear and fifteen carrying teeth. 100
45. In a totalizer the combination of a carrying wheel and a numeral wheel geared thereto, the number of numerals on the numeral wheel and the number of teeth on the carrying wheel being such that when both numbers are divided by their greatest common divisor the quotients are prime to each other.

In witness whereof, I have hereunto subscribed my name in the presence of two witnesses.
